DESIGN FOR A TOY VEHICLE

Robert F. Kuntz, Santa Monica, Calif.

Application December 10, 1945, Serial No. 124,581

Term of patent 3½ years

(Cl. D34—15)

To all whom it may concern:

Be it known that I, Robert F. Kuntz, a citizen of the United States and a resident of Santa Monica, in the county of Los Angeles and State of California, have invented a new, original, and ornamental Design for a Toy Vehicle, of which the following is a specification, reference being had to the accompanying drawings, forming a part thereof.

Figure 1 is a perspective view of a toy vehicle showing my new design;

Figure 3 is a front view of the toy vehicle;
Figure 4 is an end view of the same;
and
Figure 6 is a bottom view of the same.

I claim:

The ornamental design for a toy vehicle, substantially as shown.

ROBERT F. KUNTZ.
